[57] CLAIM

The ornamental design for a storage box lid, as shown and described.

DESCRIPTION

FIG. 1 is a perspective view of a new design for a storage box lid;

FIG. 2 is a top plan view of the storage box lid shown in FIG. 1;

FIG. 3 is a bottom plan view of the storage box lid shown in FIG. 1;

FIG. 4 is a right side elevational view of the storage box lid shown in FIG. 1, the left side elevational view being the same;

FIG. 5 is a front elevational view of the storage box lid shown in FIG. 1, the rear elevational view being the same; FIG. 6 is a perspective view of an alternative embodiment of a new design for a storage box lid in accordance with the present invention;

FIG. 7 is a top plan view of the storage box lid shown in FIG. 6;

FIG. 8 is a bottom plan view of the storage box lid shown in FIG. 6;

FIG. 9 is a right side elevational view of the storage box lid shown in FIG. 6, the left side elevational view being the same;

FIG. 10 is a front elevational view of the storage box lid shown in FIG. 6, the rear elevational view being the same; FIG. 11 is a perspective view of an alternative embodiment of a new design for a storage box lid in accordance with the present invention;

FIG. 12 is a top plan view of the storage box lid shown in FIG. 11;

FIG. 13 is a bottom plan view of the storage box lid shown in FIG. 11;

FIG. 14 is a right side elevational view of the storage box lid shown in FIG. 11, the left side elevational view being the same; and,

FIG. 15 is a front elevational view of the storage box lid shown in FIG. 11, the rear elevational view being the same.
